Hays.

UNITED STATES PATENT OFFICE.

DAVID BOURQUE, OF AMESBURY, MASSACHUSETTS, ASSIGNOR TO G. W. J. MURPHY COMPANY, OF AMESBURY, MASSACHUSETTS, A CORPORATION OF MASSACHUSETTS.

BUFFER.

Application filed October 12, 1922. Serial No. 594,018.

This invention relates to buffers or cushions and the object is to provide a device embodying a resilient cushioning member which may be conveniently adjusted for 5 wear but which will remain in position during use to effect its function in the most satisfactory manner. In the embodiment of the invention here illustrated I have shown as an example thereof a buffer adapted to 10 be applied to a door such as the door of an automobile to cushion the shock of closing. In this form the invention might in one aspect be considered as an improvement on the device disclosed in Letters Patent 15 1,385,448 to John H. Harward. As compared with the device of that patent I provide a more refined construction and in particular one in which the buffer block is securely held in its operative position at all 20 times.

My invention will best be understood by reference to the following description of the particular illustrative embodiment thereof illustrated in the accompanying drawings, 25 wherein:

Fig. 1 is a section through a door adjacent the jamb showing in elevation the jamb lining with a device embodying my invention applied thereto;

Fig. 2 is a similar view with part of the jamb lining broken away to show the device in longitudinal section;

Fig. 3 is a section on the line 3—3 of Fig. 2;

Fig. 4 is the top plan of the casing utilized in the device and is on a larger scale; and

Fig. 5 is a section on the line 5—5 of Fig. 4 showing also a cooperating part in separated position.

Referring to Figs. 1 and 2 of the drawings, I have there shown a portion of the jamb lining 5 of a door having the usual rebate 7 in which the door 9 is adapted to close. The device here shown as an example of my invention is adapted to be applied to the jamb lining and to present a cushion against which the door will close. Herein the device is organized as a unit adapted to be mounted in a suitable mortise 11 in the jamb lining.

The device shown comprises a suitable casing 13 which may be secured by means of

screws, as shown, in the mortise 11. The casing may be of parallelopipedal form and is provided with an open outer end, facing the rebate 7 and preferably has an open top or face at the outer side of the jamb lining (see Fig. 3). I prefer to dispense with any removable top or cover for closing this open side since the preferred form of my invention as hereinafter explained, provides means for positioning a buffer block in the casing in such manner that it will not become displaced through such an open top while always readily accessible for adjustment therethrough. Housed within the casing is the buffer proper or cushion consisting of a suitable block 15 of resilient material such as rubber adapted to fit the casing and having an end projecting from the open end thereof to contact with the door 9 as illustrated in Figs. 1 and 2. To hold the block 15 in the casing and in particular to provide for adjustment of the former as the projecting end is worn by use I may imbed in the block a bowed metal spring 17 having its convexity presented towards the open end of the casing and the ends 19 of which are exposed at the sides of the block and form lugs adapted to engage in grooves 21 at the side of the casing, conveniently formed by striking up the metal thereof into the form of a series of ratchet teeth 23. In Fig. 3 I have illustrated the spring 17 as provided with cut away portions 25 to prevent its being too stiff and it may be provided with openings 27, therein through which the rubber on the block 15 may extend so that the block is firmly bonded in position on the spring.

Difficulty is experienced in door buffers because the projecting end of the cushion may be caught in use and twisted out of position. An open topped casing such as I have here illustrated presents various advantages of simplicity and cheapness and also that of providing for access to the cushion at all times without the necessity for the use of tools. Thus, in the example of the invention shown the cushion may be lifted or pried out of the open top of the casing and re-inserted so that the ends 19 of the spring rest in one of the grooves 21 further to the right, viewing Fig. 2, than is shown and thus the wear ing away of the outer end of the cushion

through use may be compensated for. Referring to Fig. 2, it will be noted in striking up the teeth 23 I have placed them adjacent to the middle portion of the casing between its

5 ends and that the spring 17 is also placed substantially centrally in the block 15 remote from the rear end thereof so as to provide a considerable body of rubber at the rear of the spring instead of so arranging 10 it that the lugs 19 formed by the end of the spring would be presented at the extreme rear end of the block. If now a force is applied to the end of the block 15 at the right in Fig. 1 tending to move it towards the 15 reader and it tends to turn on the lugs 19, such turning movement will be resisted by the body of the block at the rear of the spring. By a slight sacrifice of range of 20 adjustability a more adequate positioning of the block in practice is provided for.

Referring now to Fig. 4, in the preferred form of my invention in striking up the teeth 23 to form the grooves 21 they are arranged at an angle sloping inwardly and 25 rearwardly from the open top of the casing and the ends of the spring are correspondingly disposed. The expansive action of the spring, therefore, exerts a tendency tending to draw the block downwardly into the casing and to prevent its displacement from the open side thereof. To displace the block 15 requires not only a transverse blow but a force exerted lengthwise of the casing and the spring is thus more firmly held in position. 30 In the action of the buffer, as the door closes against the end thereof and strikes a blow on the block 15, the tendency is to drive the lugs 19 inwardly along the slanting grooves and seat the block against the bottom of the casing.

As a further security, as is best illustrated in Fig. 5, the bottoms of the grooves may flare from the open side of the casing towards the back to provide an undercut seat 45 so that the distance between opposed grooves is greater at the side nearer the back than at the side adjacent the open top of the casing. In striking up the teeth from the body of the casing as herein shown, the metal of the wall 50 may be pressed outwardly to provide this increased distance as is indicated in dotted lines at 27 in Fig. 3 but in the subsequent formation of the casing this projecting rib may be slabbed off or rolled down. It will 55 be seen from Fig. 5 that the wall of the casing is somewhat thinner adjacent the right hand side of the teeth than at the left. This construction providing an inward flare on the bottoms of the grooves is convenient in 60 practice but is somewhat difficult to illustrate. Since the drawing represents a preferred mechanical embodiment of the invention, I have herein explained this matter in considerable detail. It will be, of course, 65 understood that the flare of the bottoms of

the grooves might be provided for in any desired way and that the particularity of this description is simply to prevent a possible misunderstanding of the disclosure.

The ends 19 of the spring 17 are bevelled 70 to correspond with the flare of the seat. The buffer is inserted by a slight compression of the spring 17 and a movement of the entire cushion inwardly through the open top of the casing from the position shown in Fig. 5 75 towards the left and the spring expanding is caught as in a dove-tailed joint in the grooves 21. Because of the resiliency of the spring the cushion may be removed when desired for purposes of adjustment but the 80 construction effectually aids in preventing accidental displacement.

In the form of invention shown embodying the use of a bowed spring 17 to provide for holding the cushion on the casing not 85 only is the resiliency of the rubber to the right of that spring utilized in the cushioning action but the spring itself may yield to the heavier shocks. The spring grips firmly in the casing and without loose play 90 and although the contacting of the lugs 19 with the walls of the casing is between metal and metal there is no rattling and noise.

I have described in detail the particular embodiment of my invention here shown by 95 way of example together with all the details of construction which may preferably or conveniently form a part of such a device. It will be understood, however, that all these details are not essential to my invention in 100 the broader aspects thereof and the subject matter of invention exemplified by the above specific disclosure which I claim as new and desire to secure by Letters Patent I shall express in the following claims. 105

Claims:

1. A buffer of the class described comprising a casing having an open top and an open end and interior teeth at the sides, a resilient block received in the casing and adapted to project from the end thereof and a spring imbedded in the block and having its ends projecting to engage the teeth. 110

2. A buffer of the class described comprising a casing having an open top and an open end and an open side and interior teeth at the sides, a resilient block received in the casing and adapted to project from the end thereof and a bowed spring associated with the block presenting its convexity towards 115 the open end of the casing and its ends to said teeth. 120

3. A buffer of the class described comprising a casing having an open end and having interiorly presented grooves in medial position at its sides, a resilient block having holding means associated therewith comprising lugs to seat in said grooves and having a substantial body rearwardly thereof to engage the rear of the casing and prevent tip- 125 130

ping of the block under forces applied to an end thereof projecting from said open end of the casing.

4. A buffer of the class described comprising a casing having an open end and a resilient block received by the casing to project from the open end thereof and having means between the ends thereof for adjustably engaging it with the walls of the casing and 10 providing a substantial body forward of said engaging means and receiving the buffing shock and a substantial body at the rear thereof cooperating with the casing to prevent tilting of the block under buffing shock.

15 5. A buffer of the class described comprising a casing having an open end, grooves at the sides of the casing having flaring bottoms and a buffer block having holding means associated therewith comprising relatively resiliently compressible lugs adapted to fit the 20 grooves.

6. A buffer of the class described comprising a casing having an open end, opposed grooves in the side walls thereof together constituting an undercut seat and a buffer block having a bowed spring imbedded therein presenting its ends at the sides thereof, said ends being bevelled to fit the seat.

7. A buffer of the class described comprising a casing having an open end, opposed inwardly and rearwardly sloping grooves in the side walls thereof together constituting an undercut seat and a buffer block having a bowed spring imbedded therein presenting its ends at the sides thereof, said ends being bevelled to fit the seat.

8. A buffer of the class described comprising a casing having an open end and an open top and having sides provided with grooves sloping inwardly and rearwardly from said open top and a buffer block adapted to project from the open end of the block and having a bowed member associated therewith

presenting its convexity towards the open end of the casing and having its ends seating 45 in the grooves.

9. A buffer of the class described comprising a casing having an open end and an open top through which the hereinafter mentioned block may be inserted and having series of 50 teeth along its sides and a buffer block received in said casing having lugs presented at its sides to engage with said teeth, which lugs are resiliently compressible towards one another.

10. A buffer of the class described comprising a casing having an open end and an open top through which the hereinafter mentioned block may be inserted and having series of 55 teeth along its sides and a buffer block received in said casing having lugs presented at its sides remote from the rear end thereof to engage with said teeth, which lugs are resiliently compressible towards one another.

11. A buffer of the class described comprising a casing having an open end and an open top through which the hereinafter mentioned block may be inserted and having its sides formed to provide an undercut seat and a buffer block received in said casing having 60 bevelled lugs presented at its side, which lugs are resiliently compressible towards one another to be entered into said seat and expansively to engage therewith.

12. A buffer of the class described comprising a casing having an open end and an open top through which the hereinafter mentioned block may be inserted and having its sides formed to provide an undercut seat and a buffer block received in said casing having 70 associated therewith a bowed flat spring having bevelled ends to fit said seat.

In testimony whereof, I have signed my name to this specification.

DAVID BOURQUE.
